UNITED STATES PATENT OFFICE.

MYRON BRANDEBERRY, OF BLOOMDALE, OHIO.

BIT HAMMER AND JOINT BREAKER.

Application filed December 11, 1922. Serial No. 606,149.

To all whom it may concern:

Be it known that I, MYRON BRANDEBERRY, a citizen of the United States, residing at Bloomdale, in the county of Wood and State 5 of Ohio, have invented new and useful Improvements in Bit Hammers and Joint Breakers, of which the following is a specification.

This invention relates to a bit hammer

10 and joint breaker, the general object of the invention being to provide a hammer carrying member and an anvil carrying member, with means for reciprocating the hammer member to bring one hammer thereon 15 against the bit on the anvil member and for oscillating the hammer member to bring another hammer against an article on the anvil member.

Another object of the invention is to provide means whereby both members may be moved along a track, with means for connecting the two members together by a flexible member which is wound upon a drum on the hammer carrying member.

25 A further object of the invention is to provide means whereby different tools can be placed on the hammer carrying part of the hammer member.

The invention also consists in certain other 30 features of construction and in the combination and arrangement of the several parts, to be hereinafter fully described, illustrated in the accompanying drawings and specifically pointed out in the appended claims.

35 In describing my invention in detail, reference will be had to the accompanying drawings wherein like reference characters denote like or corresponding parts throughout the several views, and in which:—

40 Figure 1 is a plan view of the invention. Figure 2 is a side view thereof.

Figure 3 is a sectional view on the line 3—3 of Figure 2.

Figure 4 is a sectional view on the line 4—4 of Figure 1.

Figure 5 is a plan view showing how the invention is used to break joints.

Figure 6 is a sectional view on line 6—6 of Figure 2.

50 Figure 7 is a detail perspective view of the three-armed lever with its vertical arm removed.

Figure 8 is a detail perspective view of the supporting stem for the three-armed lever.

55 Figure 9 is a detail perspective view of the vertical arm of the three-armed lever.

Figure 10 is a detail view of the removable hammer carried by the three-armed lever.

Figure 11 is a detail perspective view of a chisel supported on the hammer end of the 60 three-armed lever.

Figure 12 is a detail longitudinal sectional view through the hammer end of the three-armed lever with the removable hammer supported thereby.

65 In these views, 1 indicates a track, preferably of semi-circular shape, or substantially so, the top of which being formed with ratchet teeth 2, excepting the front end, which is left plain. The sides of the track 70 are grooved to receive the tongues of the hammer carrying member 3 and the anvil carrying member 4, so that these members are movably mounted on the track. The member 3 can be locked to the track by the 75 locking means 5 and the member 4 is provided with the dogs 6 which engage the ratchet teeth and act to hold the member 4 against movement in one direction on the track. Member 3 carries a drum 7, provided with ratchet means 8, and a chain 9 is connected with the drum and with the member 4. Thus the two members are connected together by the chain. A stem 10 fits in a socket formed in the member 3, said 80 stem having a spherical head which engages a socket formed in a three armed lever 11, so that the lever is movably mounted on the stem. The arms 12 and 13 form handles, the arm 13 being vertically arranged, and 85 the arm 14 has a hammer formed at its end, as shown at 15 and this arm has a dove-tail slot 16 in its under part to receive a hammer 17, which is provided with a dove-tailed end to engage the slot. A set screw 18 holds the 90 hammer 17 in position. A chisel 19 is adapted to fit over the hammer 15 and to be held thereon by a set screw 20 and a wrench 21 is also adapted to have its socketed part fit over said hammer and to be fastened in position by the set screw 22. The jaws of this wrench form a circle when 95 closed, the movable jaw being hinged to the stationary jaw and the movable jaw being held in place by the latch means shown at 23. When either the chisel or wrench is used the under hammer 17 is removed.

100 Any suitable means may be used to actuate the device, the drawings showing a cranked wheel 24, the crank of which is connected to a rod 25 which has its other end 110 connected with the member 3 when the

hammer lever is to be reciprocated to use the hammer 15, and said rod is connected with the handle 13 when the lever is to be rocked on the spherical head to bring the hammer 17 into action. The handles are used for guiding the hammers. As will be seen the member will be reciprocated on the track when the rod 25 is connected therewith and thus the hammer lever will also be moved back and forth to bring its hammer 14 against the bit on the anvil member, the hammer being guided by the handle 12. This hammer is useful in shaping the cutting ends of bits. When the lever is rocked the under hammer gives a vertical blow and is useful for shaping the bodies of bits. The chisel will be used for cutting grooves in the bits for the water to pass through and the wrench is used for uncoupling well pipes and the like as shown in Figure 5.

In using the aforesaid assemblage of elements as a bit hammer, a bit is placed on the anvil carrying member with its cutting surface directed toward the reciprocating hammer carrying member. After so arranging the bit the crank 24 is rotated toward the anvil carrying member, before starting the motor, not shown, whereupon the anvil carrying member is disposed a sufficient distance from the outward limitation of the thrust of the hammer 15 to procure the desired impact on the face of the bit. With these elements so arranged, the bit is held on the anvil by one attendant and the hammer is guided toward and in contact with the face of the bit by a second attendant through the instrumentality of the arm 12, as the crank continues to reciprocate the hammer carrying member.

As the anvil carrying member is disposed so the face of the bit lies sufficiently within the range of the reciprocating hammer to produce the proper impact of the hammer thereagainst as it reaches its outward stroke, the blow on the anvil is not severe and is taken up through the dogs 6 which engage the teeth 2 of the track 1.

When the hammer is used to shape the shank or other portions of the bit the hammer 17 is secured to the arm 13 and the arm 14 is rocked in a vertical plane above the bit through the instrumentality of the reciprocating rod 25 which is released from the hammer carrying member and fastened to the arm 13. Prior to so connecting the rod 25 to the arm 13 the hammer carrying member is secured to the track 1 by the locking means 5 so it will remain in proper fixed relation to the anvil carrying member to permit the hammer 17 to repeat its blows on the bit as the rod 25 continues to reciprocate. During this movement the attendant guides the arm 14 through the instrumentality of the arm 13.

In using the elements of this invention

to break the joints of well pipes, the wrench 21 is engaged with the section of pipe to be turned with the hammer carrying member disposed on the track 1 in close proximity to the curved portion thereof and at the desired outward limit of thrust of the reciprocating rod 25 and, upon causing the crank to be rotated by the motor, not shown, the reciprocating rod 25 will turn the section of the pipe to which it has previously been fastened and return the wrench for subsequent grips on the pipe during the reciprocations of the rod 25.

In order to permit the hammer carrying member to reciprocate in a straight line while the hammer arm attached thereto travels concentrical with the well pipe, the proper degree of slip is permitted through the fastening means between the wrench and arm 14.

In order to utilize the hammer carrying member and anvil carrying member to try pipe joints, that is to ascertain whether or not the pipe joints are tight, the hammer carrying member, with the arm 11 fastened to the pipe through the instrumentality of the wrench, is drawn toward the previously secured anvil carrying member through the instrumentality of the chain 9 and ratchet mechanism 8.

Having thus described my invention what I claim as new is:—

1. A device of the class described, comprising a hammer carrying member, an anvil carrying member, a hammer carrying lever movably mounted on the hammer carrying member, handles on the lever, an actuating member and means for connecting the actuating member to the hammer carrying member to reciprocate or rock it.

2. A device of the class described, comprising a hammer carrying member, an anvil carrying member, a track supporting the hammer and anvil carrying members, means for slidably retaining the hammer and anvil carrying members on the track, a three-armed lever swivelly carried by the hammer carrying member, two of the arms being handles and the other having a hammer area at its end with a hammer receiving slot adjacent its end, means for reciprocating the hammer member or for rocking the lever thereon and means for flexibly connecting the hammer carrying member with the anvil carrying member.

3. A device of the class described, comprising a hammer carrying member, an anvil carrying member, a curved track supporting the hammer and anvil carrying member, a three-armed lever swivelly carried by the hammer carrying member, one of the arms having a hammer area at its end and the other arms disposed on radii to the swivel point of the lever approximately at right angles to one another, a removable

hammer carried by that arm of the lever having a hammer area at its end, an actuating member for the hammer carrying member and means for transmitting either a reciprocating or rocking motion to the three-armed lever.

4. A device of the class described, comprising a curved track having ratchet teeth thereon, a pair of members slidably mounted on the track, dogs carried by one member for engaging the teeth of the track, means for locking the other member to the track, a three-armed lever swivelly mounted on the second mentioned member, a removable hammer carried by one arm of the lever, a rod connected to that arm of the lever disposed approximately at right angles to the hammer carrying arm, and means for transmitting rocking motion to the lever.
5. A device of the class described, comprising a track partially curved, ratchet teeth in the curved portion of the track, an anvil carrying member slidably carried by the track, dogs carried by the anvil carrying member for engaging the teeth of the track, a hammer carrying member slidably carried by the track, means for locking the hammer carrying member to the track, a three-armed lever swivelly supported on the hammer carrying member, one of the arms

having a hammer area at its end and the other two arms disposed to form handles, a drum carried by the hammer carrying member, a flexible element connecting the anvil carrying member with the drum and means for winding the flexible element on the drum.

6. A device of the class described, comprising a curved track, a hammer carrying member slidably carried by the track, a three-arm lever carried by the hammer carrying member and having two of its arms disposed in approximate horizontal alignment and its other arm disposed at right angles thereto, a wrench secured to one end of the horizontally disposed arm of the lever in gripping contact with a well tube, a rod connected to the hammer carrying member and reciprocating means connected to the rod.

7. A device of the class described, the combination with an anvil carrying member movably secured upon a track, of a hammer and means for selectively transmitting a reciprocating or rocking motion to the hammer.

In testimony whereof I affix my signature.

MYRON BRANDEBERRY.
